UNITED STATES PATENT OFFICE.

HARRY A. HOUSEMAN, OF PHILADELPHIA, PENNSYLVANIA, ASSIGNOR TO THE STANDARD MACHINE COMPANY, OF PENNSYLVANIA.

CIRCULAR-KNITTING MACHINE.

SPECIFICATION forming part of Letters Patent No. 640,769, dated January 9, 1900.

Original application filed July 7, 1898, Serial No. 685,303. Divided and this application filed May 20, 1899. Serial No. 717,666. (No model.)

To all whom it may concern:

Be it known that I, HARRY A. HOUSEMAN, a citizen of the United States, residing at Philadelphia, county of Philadelphia, and State of Pennsylvania, have invented a new and useful Improvement in Circular-Knitting Machines, of which the following is a full, clear, and exact description, reference being had to the accompanying drawings, which form a part of this specification.

My invention consists in certain improvements in circular-knitting machines designed for making tubular goods, and especially designed to make stockings.

15 The improvements generally consist in the following: first, forming a stocking or tubular fabric having a variety of colors and regulating at will a predetermined number of courses of any-colored thread and providing 20 for any desired combination of color; second, adding a reinforcing-thread at the desired point in the formation of the fabric where the reinforced thread is used only in a portion of the course and yet maintaining the 25 tension of the thread at all points of the course substantially uniform, and, third, removing the reinforcing-thread of the heel and toe at the desired point when its desired action is completed and bringing it into action again at 30 the desired point.

I will first describe my invention as embodied in the machine illustrated in the accompanying drawings and then point out the same in the claims.

35 In the drawings, Figure 1 is a front view of the machine with my improvement. Fig. 2 is a side elevation of the same. Fig. 3 is a plan view. Fig. 4 is a front view of the mechanism for controlling the thread-carriers. Fig. 40 5 is a side view of the same. Fig. 6 is a plan view of the same. Fig. 7 is a detail view of one of the thread-carriers. Fig. 8 is a detail view of the pawl and ratchet-wheels for operating the pattern-chain for controlling the 45 mechanism for the thread-carriers. Fig. 9 is a side elevation of the reinforcing-thread-controlling mechanism. Fig. 10 is a plan view of the same. Fig. 11 is a detail view of the shears. Fig. 12 is a detail view of the clamp. 50 Fig. 13 is a side elevation of the mechanism

for operating the reinforcing-thread-controlling mechanism. Fig. 14 is a detail section showing the connections for raising the cylinder when reinforcing the sole. Fig. 15 is a detail view of the pawl-holding mechanism. 55 Fig. 16 is a detail plan view of gear-wheel E⁶, cam h², and a portion of large end H' of the lever. Fig. 17 is a view similar to Fig. 9, showing the parts in position to feed both threads. Fig. 18 is a perspective view of block M. 60

I will first describe that portion of my invention set out in clause first in the statement of invention. There is a class of stocking called "striped," in which there are a plurality of colors formed by courses or stripes of different colors. This portion of my invention has for its object to produce this upon a circular-knitting machine automatically without stopping the machine. In the machine shown in the drawings I accomplish this in 70 the following manner:

A is the driving-wheel on shaft a, connected with the source of power in the ordinary manner. Upon the shaft a is the bevel-gear A', meshing with the gear B, loose upon the shaft b. 75

B' is a pinion upon shaft a meshing with pinion B², to which is connected the connecting-rod B³, connected to lever B⁴, pivoted at one end to the frame of the machine and at the other end to the rack B⁸, which operates 80 the gear B⁵, loose upon the shaft b.

B⁶ is a gear fixed upon the shaft b and operates a gear on the cam-cylinder C.

C' is a clutch feathered upon shaft b and adapted to engage either gear B or gear B⁵, 85 and according to which it is connected the cam-cylinder is rotated or reciprocated. The clutch is shifted automatically at the desired points through the action of the pattern-chain C¹¹ and mechanism fully described in United States Letters Patent issued to me April 30, 1895, No. 538,518.

C³ is the needle-cylinder.

D D' D² D³ D⁴ are a plurality of thread-carriers, through all of which an independent 95 thread passes, except D, through which two threads pass, one of which is normally out of action, the purpose of which will be herein-after fully described. These thread-carriers consist of levers pivoted to a carriage D⁶, se- 100

cured to cam-cylinder C, so as to travel with it. The inner end of each lever is formed in two parts, the part $d_1 d_2 d_3 d_4$, respectively, of each lever sliding on the other part. To one 5 end of each thread-carrier lever is secured a vertical roller, (denoted, respectively, $d_5 d_6 d_7 d_8$ $d_9 d_{10}$.) Upon the other end of these thread-carrier levers are the pins d_{11} , each of which rests in a cam-slot d_{12} in the carriage D⁶. This 10 slot is inclined upwardly and toward the needle-cylinder. The rollers $d_5 d_{10}$ are arranged at different vertical heights and in the rotation of the cam-cylinder are carried between the walls of the cams E E', the cam E having 15 at one point an inset e and the cam E' a projecting portion e' at a point in alinement with said inset. The thread portions of the carrier-levers are normally beyond and above the line of the needles. The lever is thrown into action 20 by its roller striking the projection e' of cam E' in the rotation of the cam-cylinder, which forces said roller so struck into the inset e, tilting the corresponding lever and depressing the lever into the same plane as the 25 needle, the depressing of the lever causing the pin to drop in its slot, causing the movable end to move inward, bringing the thread end of the lever into operative position with reference to the needle. It is thrown out of 30 action by removing the inset e and projection e' from alinement with the roller of said lever, so that in the rotation of the cam-cylinder it strikes the cam E, which forces it in the opposite direction, reversing the position of the 35 corresponding lever and moving its thread end out of operative position.

From the above description it is apparent that in the movement of the cam-cylinder the thread-carrier lever whose roller is in alinement with the inset e and projection e' will 40 be moved to operative position, or if previously thrown into operative position will remain so, while all the other levers will encounter the plain surfaces of cams E and E' 45 and be thrown out of operative position or remain out of operative position, the projections e' and inset e being sufficient for one roller only. In order to control at will or in a predetermined manner the use of these different thread-carriers, whose thread may be 50 of different colors, I provide means for automatically and in a predetermined manner shifting the cams E and E' to bring the inset e and projection e' in alinement with any of the desired rollers. These means are as follows: The cams E and E' are secured to block E², Fig. 4, which block E² is supported upon rod E³, which is capable of vertical movement 55 in guides e² e³. The lower end of this rod E³ rests upon the end of lever E⁴, pivoted at e⁴ to the frame of the machine. Connected to this lever, between its pivot-point and the rod E³, is the projection e⁵, which rests upon the 60 surface of the pattern-wheel E⁵. The surface 65 of this wheel is made up of plates e⁶, which are detachably secured to the wheel E⁵ and are of different heights. According to the

height of the plate e⁶, upon which the projection e⁵ rests, the elevation of the rod and the position of the inset e and projection e' of cams E and E' with reference to the rollers of the thread-carrier levers is determined, and hence the thread-carrier which is in action. By arranging these plates upon the wheel in a predetermined order in the rotation of the 70 wheel the thread-carriers will be thrown in and out of action according to this order, and thus combination of colors in the stocking may be obtained. Any arrangement desired may be made by placing the plates upon the 75 wheel to conform thereto. The pattern-wheel is moved to cause the shift of thread-carriers at the desired points in the construction of the fabric in the following manner: Secured to the bevel-gear B is the gear E⁶, which 80 meshes with bevel-gear E⁷, to which a connecting-rod is secured. The other end of the connecting-rod is secured to the rocking lever E⁸. Pivoted to said lever E⁸ are the two pawls e¹⁶ and e¹⁷. The pawl e¹⁶ works in the ratchet 85 E²⁸, loose upon the shaft e⁹, and also the ratchet E⁹, secured upon the same shaft. Upon this shaft is wheel E¹⁰, carrying the striping pattern-chain E¹¹. The teeth in the ratchet-wheels E²⁸ and E⁹ are in alinement with each 90 other, but alternate teeth upon ratchet E²⁸ are higher than the teeth of the ratchet E⁹, so that the pawl e¹⁶ acts upon the ratchet E⁹ only every other throw. This is done to avoid a 95 pattern-chain of too great length, and the 100 striping pattern-chain is moved on alternate throws of the pawl.

The pawl e¹⁷ works in the ratchet E¹², connected to wheel E⁵. This pawl is held out of action in the following manner: e¹⁰ is a rock-shaft having the spring e¹¹. Upon this shaft are the levers e¹² and e¹³. The outer end of lever e¹² rests against a pin e¹⁴ upon the pawl e¹⁷ and by the action of the spring e¹¹ holds said pawl out of engagement with the teeth of ratchet E¹². The lever e¹³ is in alinement with projections e¹⁵ upon the chain E¹¹, and when struck by said projection the shaft e¹⁰ is rocked, causing lever e¹² to be depressed, allowing the pawl e¹⁷ to engage the teeth and 115 move the pattern-wheel. In order to prevent the pawl e¹⁷ from being forced out of action as soon as the projection e¹⁵ has passed and until said pawl has done its work, I provide the following means: e¹⁶ is a lever pivoted at 120 e¹⁸, acted upon by spring e¹⁷. When the lever e¹² falls, the spring e¹⁷ turns the lever e¹⁶. Upon this lever e¹⁶ is an inset e¹⁹, which on the turning of this lever e¹⁶ engages a pin e²⁰ on lever e¹² and locks said lever. When the 125 pawl e¹⁷ is rocking forward and rocking the ratchet-wheel e¹⁰, it strikes the lever e¹⁶, turning it on its pivot-point, releasing the pin e²⁰ from the inset e¹⁹, and if the lever e¹³ is then released from the projection e¹⁵ the lever e¹² 130 will move up, forcing the pawl e¹⁷ out of operative position. This occurs when the pawl has retracted to proper position for the next tooth.

By arranging the plates on the pattern-wheel I can at will arrange the color order, and by arranging the projections on the pattern-chain I can at will arrange the extent of any 5 one color in the fabric.

The next portion of my invention consists in adding a reinforcing-thread at the desired point in the formation of the fabric when the reinforce-thread is used only in a portion of 10 the course, and yet maintain the tension of the threads at all parts of the course substantially uniform.

It is often desirable to have the sole of a stocking of double thread, while the top of the 15 foot is of single thread. This necessitates two threads in one portion of the course and one in the other. If the tension were maintained uniform throughout this course, there would either be too great tension where the 20 double thread was used or too little tension where the single thread was used. The purpose of my invention is to change the tension in the course, so that the portions with single and double thread will have like tension.

25 In addition to the thread-carriers D and D⁴ there is a thread-carrier D⁵, which is like the other thread-carriers, having a movable part d⁵ and roller d¹¹, but the roller d¹¹ is in such position as not to be affected by the cams E E'.

30 Upon the frame of the machine on opposite sides are the cams G and G'. The cam G is a fixed cam and always in alignment of movement of roller d¹¹ and of such shape as to lift the thread-carrier lever D⁵ and throw it out of 35 action. The cam G' is a movable cam, adapted to be moved in and out of alignment with the roller d¹¹, and its shape is such that when in alignment with the roller d¹¹ the lever D⁵ is thrown into operative position. It thus may be

40 seen that so long as the cam G' is out of action the thread-carrier D⁵ is out of action throughout the entire course, but when the cam G' is in action the thread-carrier D⁵ is in operation for half the course and out of action for the 45 other half. I provide the following means for controlling this cam G' and bringing it into action and moving it out of action at the desired points. It is well known that in knitting stockings upon a circular-knitting ma-

50 chine first a portion of tubular goods is formed, then the toe, then the foot, then the heel, and then the leg, the superfluous tubular portion before the toe being removed. It is also well known that when knitting the toe 55 and heel the cam-cylinder is reciprocated, while in knitting the foot and leg it is rotated. The change from rotation to reciprocation in this machine is accomplished in the manner fully described in my Letters Patent No.

60 538,518, hereinbefore spoken of. Generally speaking, it is accomplished by shifting the clutch C' into engagement with either the rotating gear B or reciprocating gear B⁵. The shifting is accomplished by the clutch-rod G⁸, 65 which in turn, by means of the rod g (to which it is connected) and the frame G⁴, to which the rod g is also connected, is in upward move-

ment of the frame operated to bring the clutch in engagement with the reciprocating gear and in the return movement is operated to 70 bring the clutch in engagement with the rotating gear. The frame G⁴ in turn is operated by the cam g' in the manner fully described in my Patent No. 538,518. The cam G' is supported by the rod g², working in guides 75 and capable of a vertical movement. Normally the rod is at such position that the cam G' is above the line of movement of the roller d¹¹ and is held there by the latch-dog G⁵, pivoted at g⁸ and having the latch end g⁴ resting under the lever. The latch-dog G⁵ has also the cam-face g¹⁵. Connected to the clutch-rod g is the arm g⁶, carrying the cam g⁷, having projecting portions g⁸, which when the frame G⁴ is down is below the latch-dog G⁵ 85 and rod g², but when the frame is elevated, which occurs at the beginning of the heel and toe, the cam g⁷ strikes the cam-face g¹⁵, lifting the latch-dog G⁵, releasing the rod g² from the latch-dog, but it is then prevented from 90 falling by the projection g⁸ resting against the said rod. After the toe has been formed to change from reciprocation to rotation of the machine the frame G⁴ and clutch-rod g fall, allowing the rod g² to descend and bring 95 the cam G' into alignment with roller d¹¹, and this extra thread is thrown in during half a course by cam G' and out of action by cam G for the other half of the course, the position of the cams being such that it is in action while the sole is knitted and out when the upper half of the foot is knitted. When the foot has been completed, the frame G⁴ lifts to change to reciprocation to knit the heel. In this movement the projection g⁸ lifts the 100 rod g², so that the cam G' is out of alignment with the roller d¹¹, and thus while knitting the heel the reinforce-thread is out of action. After the heel has been completed the frame again drops and the rod g² drops, bringing the 105 cam G' into action. The leg is now being knitted and it not being necessary to reinforce the leg beyond the ankle the parts G', g², and G⁵ are at that time brought to their initial position by the following means: Connected to 110 the rod g² is the arm g⁹, having at its free end the projection g¹⁰, which when the rod g² is in its downward position is in alignment with a lug g¹¹ on the regular pattern-chain, (which pattern-chain, its purposes other than this, 115 and its mode of operation are fully described in my previous patent, No. 538,518,) which is set to strike it at this point in the knitting. When the lug g¹¹ strikes the projection g¹⁰, it lifts it and the rod g² above the latch end g⁴ 120 of the latch-dog G⁵, and the latch-dog at that time being free from the cam g⁷ swings over and holds the rod in its upward position and the cam G' out of alignment of roller d¹¹. Fig. 13 shows the high and low positions of the 125 cam G' in full and dotted lines, respectively.

I will now describe how I obtain the proper tension on both parts of the course when the reinforce-thread is used as above described.

The needle-cylinder C³ is supported so as to be capable of vertical movement. The needle-cylinder rests upon the pin h, connected to the short end H of a lever pivoted at e⁴, the long end H' of which is bent and rests against the gear-wheel E⁵. On this gear-wheel is the cam h². A chain H² is attached at one end to the projection g⁹ on rod g², passes under the idler h³, and is attached to the long end H' of the lever. When the rod g² is lifted, the chain draws the long end H' of the lever out of alignment with cam h² against the action of the spring h⁴, and when the rod g² falls the spring h⁴ forces the long end H' of the lever into alignment with the cam h². (See Fig. 16.)

The cam h² is then at such position and of such extent as to elevate the lever H' and pin h', and with it the needle-cylinder, during that portion of the course when the thread-carrier lever D⁵ is in action. This decreases the tension in that portion of the course where the two threads are used and increases it where the single thread is used.

I provide for the retention of the idle threads in my invention by the following mechanism: I have a plurality of thread-carriers, which may be the thread-carriers D to D⁵, heretofore described, one of which is in operative position and the others out of operative position. In those carriers out of operation the thread ends and their threads are within and above the needles, while the thread end and its thread of the carrier in operation are in line with the needles.

F is a cam having a spiral face, the inner portion of the spiral being central of the needle-cylinder and the outer end being in alignment with the thread ends and threads of the carriers out of action, while the thread end and thread of the carrier in operation are beyond the outer end of said spiral. f is a projection from said cam F, which is secured to the carriage D⁶, and thus the cam revolves with the carriage.

In the operation of the machine any threads which are idle are caught by the end of the cam and moved into the center, the thread being stationary and held fixed on the last needle it was knitting. By the use of this cam F there is no danger of any loose thread being caught in the needles to the hurt of the needles or the detriment of the fabric. The loss of thread is not great, as the only unknit thread after the slack is taken up is the make of the fabric between the point at which the thread was taken out of engagement with the needles and its return to the same, the loose threads being in the center of the fabric and after taking from the machine may be readily removed without affecting the fabric.

I will now describe the remaining portion of my invention, which consists in removing the reinforcing-thread of the heel and toe when its desired action is completed and bringing it into action again at the desired point.

It is customary in knitting stockings to

knit the heel and toe with two threads, one of which, after the heel or toe is made is removed, in some cases by putting a tension on it, which causes it to break. With this the thread was not apt to be broken at the same point at all times, which allowed an uneven amount of thread to be knitted after the thread was broken. Often the thread between the break and the eye becomes frayed, which when it is brought into action again made this fabric imperfect. I will now describe my means for feeding this reinforcing thread, how it is severed at the end of its use, and how taken out of and again brought into action.

In a previous part of the specification I stated that one of the thread-carriers D to D⁴ operated two threads. This is the thread-carrier D and always operates the color used in the heel and toe, (preferably the body-color,) as well as the heel and toe reinforcing thread, whose use I am now describing.

To I⁵ are the cops carrying the threads for the thread-carriers D' to D⁵, respectively, and I⁶ is the cop carrying the additional thread for the thread-carrier D. The frame carrying the cops I' to I⁵ is connected so as to revolve with the cam-cylinder, while the frame carrying the cops I⁶ and I is stationary. The thread passes from the cop I through the guides i' i² i³ i' i⁵ and through the eyelet i⁶ of the take-up arm J, regulated by the spring j² to the thread-carrier D. When the thread from cop I is used alone, (circular work,) the take-up arm J is locked in the following manner: Projecting from the rod j is a lug j¹⁵, which rests on the longitudinal portion of said arm, preventing it from moving. The thread from the cop i⁶ (the heel and toe reinforcing thread) in its inactive position (shown in Fig. 9) passes through the movable guide K on the arm K', pivoted at k to stationary rod K² and beyond the pivot-point connected to rod j. This thread then passes through guide k² in the standard k²⁰ and between the members k³ k⁴, forming a clamp, the member k³ being movable and normally held closed by a spring k¹⁴. Secured to rod j is a projection j³, which is below the movable member k³, so that when said rod j is lifted the clamp is released. The thread then passes under the lever L, pivoted at l, and midway between the pivot-point and end of the lever passes through a lug l²⁰, projecting from block M. The thread then passes through an orifice in a projection l' of the supporting-frame. The thread passes through a guide m' in the block M, which terminates in the longitudinal passage m in the block. (See Figs. 9 and 10.)

In the position shown in the drawings the thread from cop I⁶ is below the thread from cop I, the thread from cop I being also held upward by one end of the bell-crank lever O. The other end of the bell-crank O has a slot in which rests a pin o, connected to lever P, pivoted at p. q q' are a pair of cutting-blades, of which the movable member q' has the pro-

jecting portion q^2 . A projection M^2 from the block M has the two pins m^3 , one of which is above and the other below the projecting portion q^2 . In the upward movement of the block M the pins separate the cutting-blades and in the descent of the block the pins close the cutting-blades.

Such being the parts of this mechanism and in the position shown in Figs. 9, 10, and 11, 10 I will now describe the operation by which the thread from cop I^6 is brought into action, thrown out of action, and severed.

The rod j rests upon or is connected to the rod g , and when said rod g is elevated, which 15 occurs when the machine goes on to the heel or toe, this rod j is also elevated, and when the rod g descends in passing to circular work this rod j also falls. The lever P has a bifurcated or slotted end P^{11} surrounding the rod 20 P' between the adjusting-nuts p^2 . This rod P' is capable of vertical movement and is connected to lever P^2 , pivoted at p^3 , and having the roller P^3 resting on a cam P^4 , secured on the same shaft as cam g' . With the parts in 25 the position shown in the drawings the roller rests on the high part of the cam. When the cam g' operates to lift the frame, (for the heel or toe movement of the machine,) the lower part of the cam P^4 is presented to roller P^3 30 and the rod P' drops. When the cam g' operates to depress the frame, the high part of cam P^4 is presented to roller P^3 and the rod is lifted. From this may be seen that by appropriate mechanism when the thread from 35 cop I^6 is to be used the rod j is elevated and rod P' depressed, and when it is to be thrown out of action the rod j is depressed and the rod P' elevated. The depression of rod P' causes the block M to be elevated and the upper end of the bell-crank O to be depressed 40 and the cutting-blades opened. The depression of bell-crank O allows the thread from cop I to fall, and the elevation of the block, together with the lever L , which is connected 45 to the block, lifts the thread from cop I and the two threads meet in the longitudinal passage m in the block M . The lifting of the rod j releases the clamp member k^3 and the take-up arm J . The upward movement of this arm 50 also lifts the arm K' , giving a slack to the thread from cop I^6 . The thread from cop I will then carry with it the thread from cop I^6 and the two will together go into the carrier D , the take-up arm J operating in the usual manner. At the conclusion of the heel or toe the 55 rod j falls and the rod P' rises. The fall of rod j operates rod K' to take up any slack in thread from cop I^6 , releases the clamp i^{16} of the thread from cop I , and closes the clamp k^3 60 of thread from cop I^6 . The guide i' is formed in the reduced top of the standard k^{20} . A clamp i^{16} is adapted to press down over and around the reduced top and against the shoulder formed at the bottom of the reduced top. 65 The clamp when in this position clamps the thread between it and the standard. The clamp i^{16} is connected with the take-up arm

J by an extension thereof passing through an orifice in said clamp i^{16} , as may be seen in Fig. 9. Therefore the fall of the rod j allows 70 the clamp i^{16} to open when the take-up arm J is moved, the clamp i^{16} being closed and opened by the rise and fall of the take-up arm J, the rod j locking it from movement in its downward position and allowing it to move in its 75 upward position. At the same time the rise of rod P' through the medium of block M draws down the thread from cop I^6 between the cutting-blades, which by the pins on the block M are caused to close and sever the 80 thread. The thread from cop I , by means of lever O , is lifted up to a point beyond the cutting-blades, so that it is not severed. The downward movement of lever L draws thread from the cop I^6 , so as to provide sufficient reinforcing-thread to enter the needles at the 85 next movement. (See Fig. 9.)

I do not herein claim the mechanism and means for retention of the idle threads or threads not in use which is described and illustrated in this application, as the same is described and claimed in an application filed by me July 7, 1898, Serial No. 685,303, and which application also originally contained the matter described and claimed in this application. 90 95

Having now fully described my invention, what I claim, and desire to protect by Letters Patent, is—

1. In a circular-knitting machine, in combination, a thread-carrier, a thread-supply, a vertically-movable guide through which thread passes to the carrier, and to which the thread is connected so as to move with said guide, means for moving the thread-guide, a cutting device, the movable portion of which is acted upon by said guide, means for actuating said movable guide whereby said thread is brought in alinement with said cutting device in the movement of the guide, and a clamping device through which said thread passes, said clamp having a movable member and means for operating it in the movement of said guide, and a lever connected to said guide under which the thread passes. 100 105 110 115

2. In a circular-knitting machine, in combination, a thread-carrier, a thread-supply, a vertically-movable guide, through which thread passes to the carrier, and to which the thread is connected so as to move with said guide, a cutting device, the movable portion of which is acted upon by said guide, means for moving the thread-guide and bringing said thread in alinement with said cutting device in the movement of the guide, and a clamping device through which said thread passes, said clamp having a movable member and means for operating it in the movement of said guide and a lever connected to said guide under which the thread passes intermediate of the clamp and guide. 120 125 130

3. In a circular-knitting machine, in combination, a thread-carrier, a thread-supply, a vertically-movable guide through which

thread passes to the carrier, and to which the thread is connected so as to move with said guide, a cutting device, the movable portion of which is acted upon by said guide, said 5 thread being brought in alinement with said cutting device in the movement of the guide, an actuating-lever connected to said guide, reciprocating and rotating mechanisms for the cam-cylinder, and shifting mechanism for 10 controlling and reversing the connection between the cam-cylinder and said mechanisms, and connections between said lever and said shifting mechanism.

4. In a circular-knitting machine, in combination, a thread-carrier, a thread-supply, 15 a vertically-movable guide through which thread passes to the carrier, and to which the thread is connected so as to move with said guide, a cutting device, the movable portion 20 of which is acted upon by said guide, said thread being brought in alinement with said cutting device in the movement of the guide, and a clamping device through which said thread passes, said clamp having a movable 25 member operated in movement of said guide, an actuating-lever connected to said guide, reciprocating and rotating mechanisms for the cam-cylinder and shifting mechanism for 30 controlling and reversing the connection between the cam-cylinder and said mechanisms, and connection between said lever and said shifting mechanism and connection between the movable member of said clamp and said shifting mechanism.

5. In a circular-knitting machine, in combination, a thread-carrier, a thread-supply, 35 a vertically-movable guide through which thread passes to the carrier, and to which the thread is connected so as to move with said 40 guide, a cutting device, the movable portion of which is acted upon by said guide, said thread being brought in alinement with said cutting device in the movement of the guide, and a clamping device through which said 45 thread passes, said clamp having a movable member operated in the movement of said guide, and a take-up lever connected to said 50 guide under which the thread passes, an actuating-lever connected to said guide, reciprocating and rotating mechanisms for the cam-cylinder, and shifting mechanism for 55 controlling and reversing the connection between the cam-cylinder and said mechanisms and connection between said actuating-lever and said shifting mechanism and connection between the movable member of said clamp and said shifting mechanism.

6. In a circular-knitting machine, in combination a thread-carrier, a thread-supply, 60 a vertically-movable guide through which thread passes to the carrier, and to which the thread is connected so as to move with said guide, a cutting device, the movable portion of which is acted upon by said guide, said 65 thread being brought in alinement with said cutting device in the movement of the guide, and a clamping device through which said

thread passes, said clamp having a movable member operated in the movement of said 70 guide, and a take-up lever connected to said guide under which the thread passes, and intermediate of the clamp and guide, an actuating-lever connected to said guide, reciprocating and rotating mechanisms for the cam-cylinder and shifting mechanism for controlling and reversing the connection between the cam-cylinder and said mechanisms, and connection between said actuating-lever and said shifting mechanism, and connection between the movable member of said clamp and 80 said shifting mechanism.

7. In a circular-knitting machine, in combination, a thread-carrier, a plurality of thread-supplies for said carrier, a vertically-movable guide through which said threads 85 pass to the carrier, one of said threads being connected so as to move with said guide, a lever over which the other thread passes, and means to simultaneously move said guide and lever to and from each other. 90

8. In a circular-knitting machine, in combination, a thread-carrier, a plurality of thread-supplies for said carrier, a vertically-movable guide through which said threads pass to the carrier, one of said threads being connected so as to move with said guide, a lever over which the other thread passes, a lever as P, to which the lever and guide are connected, and means to operate said lever P. 95

9. In a circular-knitting machine, in combination, a thread-carrier, a plurality of thread-supplies for said carrier, a vertically-movable guide through which said threads pass to the carrier, one of said threads being connected so as to move with said guide, a lever over 100 which the other thread passes, a lever, as P, to which the lever and guide are connected, rotating and reciprocating mechanisms, for the cam-cylinder, and mechanism to shift the driving mechanism of the cam-cylinder from the reciprocating to the rotating mechanism, and connection between said lever P and said shifting mechanism. 105

10. In a circular-knitting machine, having a rotary cam-cylinder, in combination, a 110 thread-carrier adapted to be moved in and out of action and rotate with the cam-cylinder, a cam on one side of the machine to throw the carrier out of action, and a movable cam on the opposite side to throw said 115 carrier in action, a movable support for the movable cam, a locking device adapted to hold said support so that the movable cam will be out of action, mechanisms for rotating and reciprocating the cam-cylinder and 120 means for shifting the driving mechanism from the rotating to the reciprocating mechanism and vice versa, a projecting rod connected to said shifting means in alinement with said locking device, and adapted in its 125 movement in one direction to release said locking mechanism, a projection from said rod in alinement with the movable cam-support. 130

11. In a circular-knitting machine, having a rotary cam-cylinder, in combination, a thread-carrier adapted to be moved in and out of action and rotate with the cam-cylinder, a cam on one side of the machine to throw the carrier out of action, and a movable cam on the opposite side to throw said carrier in action, a movable support for the movable cam, a locking device adapted to hold said support so that the movable cam will be out of action, mechanisms for rotating and reciprocating the cam-cylinder and means for shifting the driving mechanism from the rotating to the reciprocating mechanism and vice versa, a projecting rod connected to said shifting means in alinement with said locking device, and adapted in its movement in one direction to release said locking mechanism, a projection from said rod in alinement with the movable cam-support, a projection from the movable cam-support, a pattern-chain provided with a lug or lugs at the desired points adapted to strike said projections from the movable cam-support and elevate said support beyond the locking device.

12. In a circular-knitting machine, in combination, a plurality of independent thread-carriers radially placed, and a cam adapted when acting on a carrier to throw it into action, and means to bring said cam into operative position with reference to the desired carrier.

13. In a circular-knitting machine, in combination, a plurality of independent thread-carriers radially placed, and a cam adapted when acting on the carrier or carriers to throw said carrier out of action, and means to bring said cam into operative position with reference to the desired carrier or carriers.

14. In a circular-knitting machine, having a rotating cam-cylinder, in combination a plurality of thread-carriers adapted to be thrown in and out of action, and carried by the cam-cylinder, each carrier having an independent thread, and provided with projections, said projections being at different planes, cams between the faces of which the projections pass in the movement of the machine, said cam-faces at one point being adapted to throw the carrier striking it into action, and at other points to throw the carrier striking it out of action, and means to bring the portion of said cam adapted to throw the carriers into action in line with the desired carrier.

15. In a circular-knitting machine, having a rotary cam-cylinder, in combination, a plurality of thread-carriers adapted to be thrown in and out of action, carried by the cam-cylinder each carrier having an independent thread, and provided with projections, said projections being at different planes, cams between the faces of which the projections pass in the movement of the machine, said cam-faces at one point being adapted to throw the carrier striking it into action and at other

points to throw the carrier striking it out of action, a pattern device and connection between said cams and said pattern devices whereby said cam is operated in a predetermined manner and the carriers thrown in and out of action in a predetermined manner.

16. In a circular-knitting machine, having a rotating cam-cylinder in combination a plurality of thread-carriers adapted to be thrown in and out of action, carried by the cam-cylinder, each carrier having an independent thread, and provided with projections, said projections being at different planes, cams between the faces of which the projections pass in the movement of the machine, said cam-faces at one point being adapted to throw the carrier striking it into action, and at other points to throw the carrier striking it out of action, a support upon which said cams rest, said support being adapted to move vertically, a pattern-wheel having projections of different heights, and a connection between said support and said wheel whereby in the rotation of the wheel the support and the cam are elevated to different heights corresponding to the projections on the wheel and on the carriers.

17. In a circular-knitting machine, having a rotating cam-cylinder, in combination, a plurality of thread-carriers adapted to be thrown in and out of action, carried by the cam-cylinder, each carrier having an independent thread and provided with projections, said projections being at different planes, cams between the faces of which the projections pass in the movement of the machine, said cam-faces at one point being adapted to throw the carrier striking it into action, and at other points to throw the carrier striking it out of action, a support upon which said cams rest, said support being adapted to move vertically, a pattern-wheel having projections of different heights, and connection between said support and said wheel whereby in the rotation of the wheel the support and the cam are elevated to different heights corresponding to the projections on the wheel and on the carriers, and a pattern-chain for controlling the rotation of said wheel.

18. In a circular-knitting machine, having a rotating cam-cylinder, in combination, a plurality of thread-carriers adapted to be thrown in and out of action, carried by the cam-cylinder, each carrier having an independent thread, and provided with projections, said projections being at different heights, cams between the faces of which the projections pass in the movement of the machine, said cam-faces at one point being adapted to throw the carrier striking it into action, and at other points to throw the carrier striking it out of action, a support upon which said cams rest, said support being adapted to move vertically, a pattern-wheel having projections of different heights, a pivoted lever connected to said cam-support, an

intermediate projection from said lever resting upon said projection on the patterning-wheel.

19. In a circular-knitting machine, having a rotating cam-cylinder, in combination, a plurality of thread-carriers adapted to be thrown in and out of action, carried by the cam-cylinder, each carrier having an independent thread, and provided with projections, said projections being at different heights, cams between the faces of which the projections pass in the movement of the machine, said cam-faces at one point being adapted to throw the carrier striking it into action, and at other points to throw the carrier striking it out of action, a support upon which said cams rest, said support being adapted to move vertically, a pattern-wheel having projections of different heights, a pivoted lever connected to said cam-support, an intermediate projection from said lever resting upon said projections on the pattern-wheel, and a pattern-chain for controlling the rotation of said wheel.
20. In a circular-knitting machine, in combination, a thread-carrier consisting of a pivoted lever, an extensible portion, a projection from said extensible portion, a stationary projection having a cam-slot in which said projection rests, a projection from the main portion of the carrier, cam-faces between which the last-mentioned projection is adapted to pass in the operation of the machine, said cam-faces having a portion adapted to tilt the lever toward the needles, the projection from the extensible portion of the carrier being acted upon by the cam-slot during said tilting.
21. In a circular-knitting machine, in combination, a pattern-wheel, a ratchet for driving the same, a rotary shaft, a pawl for operating said ratchet, connection between said

pawl and the rotary shaft, a disengaging device for holding said pawl out of contact with the ratchet, a pattern-chain, a lug upon said chain, said disengaging device being in alignment with said lug and adapted when struck by said chain to release said pawl, a pivoted lever provided with an inset held by said disengaging device, and adapted to swing when said disengaging device is acted upon, a pin upon said disengaging device which said inset engages when the disengaging device is released by the pattern-chain, said lever being in line of movement of said pawl when said pawl advances.

22. In a circular-knitting machine, in combination, a pattern-wheel, a ratchet for driving the same, a rotary shaft, a pawl for operating said ratchet, connection between said pawl and the rotary shaft, a spring-acted disengaging device for holding said pawl out of contact with the ratchet, a pattern-chain, a lug upon said chain, said disengaging device being in alignment with said lug and adapted when struck by said chain to release said pawl, a spring-acted pivoted lever provided with an inset held by said disengaging device, the spring being of less strength than the disengaging-device spring and adapted to swing when said disengaging device is acted upon, a pin upon said disengaging device, which said inset engages when the disengaging device is released by the pattern-chain, said lever being in line of movement of said pawl when said pawl advances.

In testimony of which invention I have hereunto set my hand, at Philadelphia, Pennsylvania, on this 12th day of May, 1899.

HARRY A. HOUSEMAN.
